PARCEL POST WEIGHING AND STAMP
PRINTING MACHINE

William J. Pearson, Los Angeles, Calif.

Application May 29, 1929, Serial No. 367,106

6 Claims. (Cl. 235—101)

This invention relates to improvements in machines for weighing parcel post packages and for printing metered prepaid stamps for the same. More particularly my invention relates to the indicia printing of metered permit mail, which involves the use of registering mechanism to be set by a post office official for a given amount of postage, and which automatically locks the printing mechanism when such predetermined amount of postage has been exhausted.

The invention further relates to other functions performed by the same machine in the preparation of mail matter, such as weighing the matter and indicating its weight and the denominational values of the stamps affixed thereto.

The objects of my invention are:

To provide for the use, in the mailing of parcel post mail matter, of a machine adapted to print a stamp on a gummed paper tape, and to cut the tape into stamp lengths to be applied to the mail matter in the same manner as ordinary stamps;

To provide a machine wherein the stamps may be printed with various indicia and data appearing upon an indicia plate carrying lettering, upon a changeable dater in which the current date may be set up, and upon a set of numeral wheels upon which the zone, the number of pounds and the corresponding monetary denomination may be manually set up by the manual operation of keys on a key board;

To provide a machine capable of conveniently weighing parcel post matter that packages of any size or shape may be weighed thereon conveniently, having a key board section provided with a set of keys for setting up the numerals to be printed on a stamp; an index port through which may be read the scale indicator figures for all of the zones corresponding to the weight of the package; a set of indicating numeral wheels which are set up automatically upon the operation of the keys to indicate the readings of the numeral wheels within the machine, whereby errors may be detected; an error key on the key board, which may be operated to clear the machine; a permanent register readable through a port, and a downward count register readable through a similar port, the downward count register being of the character required by the postal laws and regulations governing metered permit mail, viz. a register adapted to be set by a post office official for a predetermined amount of postage, and upon the exhaustion of that amount of postage in printing stamps, to automatically lock

all of the mechanism of the machine until it has been again set by a post-office official.

To provide a parcel post weighing and stamp printing machine of such character that it will efficiently and accurately weigh all parcels up to the present limit handled by the Post Office Department, namely, seventy pounds, and to indicate by means of a visible computing scale indicator the weight in pounds, and coincidentally therewith the amount of postage required for the indicated number of pounds in each of the eight zones and the local zone according to the schedule of parcel post rates provided by the Post Office Department, which includes stamps of a denomination of 7¢ to \$6.01 inclusive. However, a machine of the character described is not limited in its use to the maximum of weight or postal denomination being used at the present time by the Post Office Department, but may be used for any amount of denomination, or any weight or number of zones, as may be required for parcel post operation by the Post Office Department.

The stamp printed by this machine will bear an imprint showing the character of the mail to which the stamp is affixed, the meter number, permit number, date, point of origin, number of the zone, the weight in pounds and the monetary denomination of the stamp, and may be printed on paper of suitable character bearing adhesive gum on the reverse side; when printed and delivered the stamp will be of the same general character as the customary adhesive postage stamp designed to be pasted on a package to be mailed.

The invention by which I accomplish these objects consists in the novel construction, arrangement and combination of parts as herein-after described and definitely pointed out in the claims and as illustrated by the accompanying drawings (15 sheets), in which—

Description of drawings

Fig. 1 is a perspective view of the parcel post weighing and stamp printing machine.

Fig. 2 is a plan view of the machine without the casing and scale mechanism, showing the printing mechanism assembled on the base plate, the various sections of the mechanism being only generally illustrated for relativity in this figure.

Fig. 3 is a front elevation of the machine in section taken on a line approximately 3—3 of Fig. 2, and showing only such mechanism as resides in the plane adjacent to that line, namely, the operating keys, their connections to the numeral wheels, the scale mechanism and the dial.

Fig. 4 is a side elevation of the machine in section taken approximately on line 4—4 in Fig. 2, showing the scale platform and weighing mechanism, the scale indicator or dial, the keys 5 and the driving gear; also the casing of the machine.

Fig. 5 is a detailed sectional view of a bearing link of the scale mechanism taken at line 5—5 in Fig. 4.

10 Fig. 6 is a sectional view of the machine taken on line 6—6 in Fig. 2, showing the casing of the machine and the door which provides access to the scale mechanism, the scale mechanism, the printing mechanism showing principally the 15 driving gears for the indicia plate roller and the conveyor belt for the paper to be printed on, the paper discharge platform and the paper roll magazine.

Fig. 7 is a view of the printing mechanism, 20 partly in section, taken on line 7—7 in Fig. 2, showing the paper roll magazine, the conveyor belt, the rotary printing drum, the numeral wheels, the dater, the paper cutting knife, the discharge platform and the moistening roller.

25 Fig. 8 is a diagrammatic view of one of the keys, namely, the key that operates to rotate the numeral wheels to the number "9", showing the lever action in two positions.

Fig. 9 is a diagrammatic view similar to Fig. 8, 30 showing the key marked "5" and its lever action.

Fig. 10 is a view similar to Figs. 8 and 9 showing the key marked "9" and its lever action.

Fig. 11 is a plan view of the scale mechanism partly in section taken approximately on line 35 11—11 in Fig. 4, showing the mechanism below the weighing platform and its position relative to the casing of the machine.

Fig. 12 is a diagrammatic plan view of that 40 part of the printing mechanism to be hereinafter termed "selector", and showing the selector finger in original position, i. e., the position assumed when the machine is clear; also showing the relative positions of the various connecting parts and one of the push rods as operated from 45 a key, namely, the key marked "4".

Fig. 13 is a diagrammatic view similar to Fig. 12, showing the selector finger at the limit of its longitudinal movement when operated by the push rod actuated by the key marked "4".

50 Fig. 14 is a diagrammatic view similar to Figs. 12 and 13, showing the selector finger at the limit of its lateral movement, from which point it is returned to its original position upon the completion of an operation of the machine for 55 stamp printing purposes, or by action of the error key.

Fig. 15 is a detailed view in side elevation of the progressive lock release mechanism for the main drive shaft (unit 163 in Fig. 2).

60 Fig. 15—A is a plan view of a fragment of the mechanism shown in Fig. 15, illustrating the movements of the lock.

Fig. 16 is a detailed view of the key locking mechanism (unit 456 in Fig. 2) actuated by the 65 main drive shaft when rotated for stamp printing purposes.

Fig. 17 is a sectional view in section of the selector mechanism (unit 150 in Fig. 2), taken approximately on line 17—17 of Fig. 2.

70 Fig. 18 is a detailed elevational view, taken approximately on line 18—18 in Fig. 2, showing the various parts of mechanism associated with the main drive shaft.

75 Fig. 19 is a sectional view of the selector, taken

on line 19—19 in Fig. 2, showing the escapement mechanism for the selector finger, and the mechanism for actuating the register shafts.

Fig. 20 is a diagrammatic view of the selector mechanism illustrated in Fig. 19, showing the selector finger as having moved one notch of the escapement mechanism.

Fig. 21 is a sectional view of the selector similar to Fig. 17, showing in detail the register set-up actuating mechanism, and in dotted lines its 10 limit of movement.

Fig. 22 is an enlarged detailed view of parts of the register set-up and actuating mechanism without the casing shown in Figs. 2 and 4.

Fig. 22—A is a detail view, partly in section, 15 showing the register set-up drive and indicator drive.

Fig. 23 is a detailed view of the drive connections for the register elevators.

Fig. 24 is a view partly in section of the 20 numeral wheel printing mechanism taken approximately on line 24—24 of Fig. 2.

Fig. 25 is a view of a detail of the printing mechanism, namely, the dater and the lock therefor.

Fig. 26 is a view in section of the dater and its 25 lock.

Fig. 27 is a view of a portion of the printing mechanism, namely, the numeral wheels, the dater and the inking device, as taken approximately on a line 27—27 in Fig. 2.

Fig. 28 is a diagrammatic view of the numeral wheel printing mechanism and the cutting knife, taken approximately on line 28—28 of Fig. 2 showing the cam and the cutting knife in the position assumed at the completion of a cutting 35 operation.

Fig. 29 is a detailed view partly in section of the cutting knife, delivery platform, moistening wheel and water tank, taken approximately on line 29—29 in Fig. 2.

Fig. 30 is a diagrammatic view partly in section of the numeral wheel printing mechanism in printing position.

Fig. 31 is a diagrammatic view partly in section of the numeral wheel inking mechanism, and 45 actuating means therefor, as taken approximately on line 31—31 in Fig. 2.

Fig. 32 is a detailed view, the opposite of the view in Fig. 15, showing the progressive release lock on the main drive shaft.

50 Fig. 33 is a view of the printed stamp.

Fig. 34 is a detailed sectional view of the inking mechanism for the printing drum.

Fig. 35 is a sectional view similar to Fig. 34, taken at right angles thereto.

Fig. 36 is a plan view of the indicia plate on the printing drum.

Fig. 37 is a side elevation of the drum shown on Fig. 36.

Fig. 38 is a detailed fragmentary view of the 60 printing drum inker tank holder.

Fig. 39 is a fragmentary view of the guide plate for the key bars.

Fig. 40 is a general view of the register mechanism from the front, parts of the operating 65 means being omitted.

Fig. 41 is a detailed view of a portion of the re-set register from the side, showing the parts in released position, whereby the said register may be re-set for a predetermined amount.

70 Fig. 42 is a detailed view of the re-set register from the front.

Fig. 43 is an enlarged view of the first three 75 numeral wheels, partly in section, of the re-

set register, showing the ratchet engagements therein.

Fig. 44 is a side elevational view of one of the wheels shown in Fig. 43.

Fig. 45 is a sectional view of the machine casing from the left, and parts of its locking mechanism.

Fig. 46 is a fragmentary view of the lock for locking the key bars when the machine is not in use.

Fig. 47 is a sectional view of the machine casing taken on line 47—47 in Fig. 45 and showing the locking mechanism.

Fig. 48 is a partial view of the scale dial showing its position relative to the index on the key board section of the casing.

Fig. 49 is a schematic diagram of the cycle of operations of the machine and its various working parts.

Fig. 50 is a detail partly in section of the clutch 20 and release lever.

Assembly element

For facility in assembling the several units of the machine and the several parts of the units; for economy in construction; for accuracy in the relating of the parts and units, and for the securing and locking of certain of the several units against unauthorized separation, I have provided an assembly element which comprises a bed 70, and as shown in Figs. 1, 3, 4, 45, and 47, certain fixed parts 71 of a casing, and certain removable and replaceable casing parts 72. To the assembly element all of the actuating parts of the machine have predetermined location and are definitely related for operation and co-action.

Scale unit

This unit comprises the recited assembly element; a supporting frame consisting of posts 73, 40 74, 75, and 76, which carry bearings 77 and 78 supporting the platform scale mechanism. The weighing platform of the scale contains a removable plate 80 for access to the scale mechanism. Plate 80 is secured to platform 79 by internal 45 locking nuts 81. Platform 79 is rockably mounted by means of platform legs 82, links 83 and link yokes 84, which are provided with fulcrum bearings 85 resting upon knife edges 86 and 87, respectively mounted in the main lever 88, short 50 lever 89, and acting as load pivots. Main lever 88 and short lever 89 are connected by load link 88' mounted in bearings 89'.

The counter poise 90 is adjustably mounted on tare beam 91, which is suspended by knife edge 55 bearings 92 on cross member 93; tare beam 91 is connected to the main lever 88 by link 93' and knife edge bearings 94 and 95. See Figs. 3 and 4.

For reading of the scale, there is provided an indicator dial 96 suspended by means of bearings 97 and 98, and held in tension by counter-weight 99, which actuates a sector 100 supported by a post 101. Connected to the sector 100 is a ribbon 102, joined with a ribbon 103 wound upon a drum 104, mounted on the shaft 105 which supports dial 96.

The dial 96 is actuated by a sector 106, supported by bearings 107 in post 108 and actuated by a gear 109 and a rack 110 positioned by roller 111; the rack is connected by bearing 112 to stabilizing fulcrum arm 113, pivoted at 114, and connected by flexible steep tape 115 to tare beam 91. Sector 106 has an adjusting member 116 to which is connected a flexible steel tape 117 which is itself connected to a steel tape 118, wound upon 75 drum 119.

Tare beam 91 is provided at its extreme end with an engaging surface 120 which comes to rest upon an adjustable stop 121 mounted on cross beam 122. A tare beam locking mechanism 123 is mounted on cross beam 122 and is operable 5 from the outside of the machine by removable handle 124 (Fig. 1). Fig. 11 further illustrates handle 124 and its engagement with rock shaft 125 and its connecting member 126, which are mounted on posts 73 and 76 in bearings 127. 10

For protection against injury and unauthorized access to the scale mechanism platform 79 is provided with an apron 128 which contacts with a felt dust protector 129 secured to the casing 72. Platform 79 is retained in position against unauthorized removal by saddles 130 (Fig. 6) which surround the various bearings and prevent displacement thereof. Authorized access to the scale mechanism is had through removal of plate 80, or through a lock door on either side of the machine. Door 131, on the right side, has a tumbler lock 132; a similar door 133 on the left side has a lock 134 and a bolt 135 to engage in a catch 136 (see Figs. 1 and 6). 15

Printing mechanism

Fig. 2, as hereinbefore described, is a general view of the bed 70 and the various units of the printing mechanism mounted thereon, each unit being so numbered.

Fig. 2 shows key unit 137; selector unit 153; numeral wheel unit 151; dater unit 152; inking unit 153; rotary printing unit 154; conveyor unit 155; paper roll magazine 156; drive mechanism 157 for conveyor unit 155 and printing unit 154; 35 main drive shaft 158; secondary shaft 159; numeral wheel unit drive 160; error rock shaft unit 161; drive shaft non-reverse unit 162; drive shaft lock and progressive release unit 163 and casing lock unit 164. 40

The registers incorporated in the machine are housed in meter casing 165, which prevents unauthorized access to them. Indicator 163 is driven directly by shafts 167 connected to the selector mechanism in selector unit 153. Conveyor unit 155 has an extension, a discharge table 168, upon which the finished stamp is deposited at the completion of a printing operation. The stamp is severed by knife unit 169 from a paper strip fed through the machine, and may be 50 moistened on the lower or gummed side by a moistening roller 170, which rotates in a water tank 171 having a filling opening 172.

The key operating mechanism 137 is composed of keys 138—0, 138—1, 138—2, 138—3, 138—4, 55 138—5, 138—6, 138—7, 138—8, and 138—9, and an error key 139; these keys are mounted on key bars 140 mounted in a bearing block 141 and tensioned by springs 142 secured to key bar arms 143 and adjustably mounted by a spring bar 60 144, adjusting screws 145 and screw supports 146 (see Fig. 4). Key bars 140 operate within guide plate 147 and are provided brackets 149 having pins 148 in their ends engaging with lever connecting arms 184 of the varying dimensions 65 necessary to the proper differential lever ratios. See Figs. 8, 9, and 10.

Selector unit 150 operates to transmit movement from the keys 138 to the numeral wheel unit 151. The selector unit is composed of a frame 173 which supports a sliding carriage 174, tensioned by springs 174' and operating in tracks 175; carriage 174 is provided with a set of transverse tracks 176 in which operate a slide 177 on which is mounted a selector finger 178. 75

(See Fig. 17). The carriage 174 has a strike plate 179, which receives the thrust from the ends of the push rods 180. The push rods operate in tracks 181 in guide plate 182; (see Fig. 21) 5 they are connected at their other ends with links 183 in turn connected to differential lever connecting arms 184 mounted at 185 on posts 186 (see Figs. 3, 4, 8, 9, and 10).

Selector finger 178, when actuated to rotate any 10 one of the wheels in numeral wheel unit 151 engages one of the rack bars 188 slidably mounted in tracks 189 in rocking frame 190. Bars 188 are provided on one end with faces 191 shaped to receive the contact of the selector finger 178, 15 and on the other end with racks 192 which engage and operate pinion gear wheels 193; each wheel 193 is secured to one of the numeral wheels 194 of numeral wheel unit 151, wherein numeral wheels 194 are loosely mounted on shaft 194' secured to 20 rocking frame 190. The rack bars 188 are tensioned by springs 195 to return them to their original position after an operation of the machine. These springs also tend to keep racks 192 in proper engagement with the pinions 193. The 25 rack bars 188 are provided on their upper surface at the end adjacent the faces 191 with a set of vertical ratchet teeth 196 spaced to provide accurate rotation of the numeral wheels 194 and acting as stops to position numeral wheels 194 to 30 accurate printing position. For this purpose a set of dogs 197 engage the ratchet teeth 196 upon the operation of selector finger 178. The dogs 197 are provided with tensioning springs 198 and are mounted on posts 199 rotatably mounted on rocking frame 190. (See Figs. 17 and 24.) Rocking frame 190 is mounted on bearings 200 on supporting frame 201; the supporting frame has an 35 adjustable stop 202 for positioning rocking frame 190, whereby contact faces 191 of rack bars 188 40 may be positioned for proper contact by selector finger 178.

Rocking frame 190 is tensioned against cam 314 and toward normal position against stop 202 by a spring 203, fastened to supporting frame 201. 45 The printing movement of rocking frame 190 is effected by cam contact between cam 314 and cam lever 204, a part of rocking frame 190 (see Figs. 3, 24, and 30).

For inking numeral wheels 194 an ink pad 205 50 is reciprocably mounted on tracks 206 and is actuated by lever 207. Lever 207 is operated by a push rod 208 riding in guides 211 and having one end provided with a roller 209 actuated by cam 210. Ink pad 205 is normally held in position 55 directly beneath numeral wheels 194 by tension spring 212.

Rocking frame 190 is provided at a point to one 60 end of the numeral wheels 194 with a removable dater device comprising a housing 213, containing a chamber 214 into which the dater 215 slides on the grooved sections 216. The dater 215 is constructed to permit the insertion of type, 217, which may be changed to provide the current date. Dater 215, when inserted in chamber 214, 65 is engaged and retained by a spring ball 218. Housing 213 is provided with a sliding pin 219, best shown in Fig. 26, which is in constant engagement with locking bar 220; when the dater 215 is seated within the chamber 214, pin 219 is 70 pressed out, moving locking bar 220 to a point where the bolt 221 is disengaged from the under face 222 of the housing 213; when the dater 215 is removed, the pin 219 moves inwardly, allowing locking bar 220 to move bolt 221 to engage 75 the face 222, thus locking the entire rocking frame

190 against any printing movement when the dater 215 is not properly seated within the chamber 214. Locking bar 220 is tensioned toward the pin 219 by spring 223 (see Fig. 25).

For printing identifying data and amount of 5 postage upon a stamp there is provided, as shown in Figs. 2, 7, 34, and 35 a rotary printing unit 154 comprising bearing arms 224 in which are bearings 225 carrying a shaft 226, to which is key mounted printing drum 227; this drum has upon 10 a portion of its face 228 (Fig. 37) an indicia plate 229 carrying the type face for a stamp 230, as best illustrated in Figs. 33 and 36. Directly above printing drum 227, and removably mounted on the bearing arms 224, is an ink well 231, comprising a 15 casing 232, a removable cover 233, guide pins 234 and supporting pins 235, held in tension by hooks 236 tensioned by springs 237 and riding on pins 238 (Fig. 38). The lower section of casing 232 provides a bearing plate 239 for the main inking 20 roller 240 and the ink distributing rollers 241, 242, 243, and 244; roller 240 is mounted in the bearing plate 239 by means of shaft 245, and is held in inking engagement with the face 230 of the indicia plate 229 by the spring hooks 236. Casing 232 is 25 provided with a discharge port 246, as best shown in Fig. 35, whereby ink contained in ink well 231 may contact with inking roller 241, to be carried thereby on to the face of the roller 240; by means of rollers 242, 243, and 244 the ink is evenly distributed, so that when the roller 240 contacts the said indicia plate face 230, the type faces thereon will be properly inked. Roller 240 is provided on either end with a flange 247 functioning as a friction wheel bearing upon the face 228 of 30 the printing drum 227, and rotating with the printing drum. By this arrangement the face of roller 240 is continually supplied with fresh ink by roller 241.

Driving gear

40

As shown in Fig. 2 the drive mechanism of the machine comprises a main drive shaft 158, a secondary shaft 159, a driving mechanism 151, and various connecting parts. To operate the drive mechanism, there is provided, as shown in 45 Fig. 1, a hand crank 248, which is removably connected to the jack shaft 249 mounted in bearing post 250; secured to shaft 249 is a drive gear 251, which meshes with a main drive gear 252 keyed to the main drive shaft 158, as best 50 shown in Fig. 4. Main drive shaft 158 is supported by bearing posts 253, 254, and 255. Bearing post 255 also supports one end of the secondary shaft 159, which is further supported by bracket bearing 256 mounted on post 74. 55

As shown in Figs. 2, 6, 7, 18, 24, 27, 28, 30, and 31, conveyor unit 155 comprises an endless belt 257 carried the forward end by idle roller 258, mounted in bearings 264, and by drive roller 259, mounted on shaft 260; shaft 260 is supported by bearing 261 and by bearing 262 in bearing plate 263. The belt 257 is supported throughout its length by a table 265, which is securely mounted on frame 266 and acts as a platen for the several 60 printing elements.

The driving gear 157 for the printing drum 227 and the conveyor unit 155 is composed of a gear train (best illustrated in Figs. 2 and 6), comprising a gear wheel 267, rotatively mounted on the main drive shaft 158, engaging with a gear wheel 70 268 keyed to the shaft 226 which carries the printing drum 227.

The main drive shaft 158 has keyed to its mutilated gear wheel 269, which engages with secondary gear wheel 270, having a divided toothed 75

periphery and a corresponding mutilated section at one side. Gear wheel 270 is geared, through gear wheel 271 and roller gear 272, with conveyor drive gear 273 keyed to shaft 260. The gears 270, 271, 272, and 273, and the main drive shaft 158, are mounted in bearings housed in bearing plate 263 (see Fig. 6).

In threading up the machine with a paper strip, it is necessary to insert the end of the paper strip under roller 274, between it and the conveyor belt 257, so that it may be carried past the several printing points. For this purpose there is provided a manually operated mechanism comprising a pin clutch 275 keyed to the main drive shaft 158. As shown in Fig. 50, the gear wheel 276 is provided with a recess 276 adapted to receive clutch pin 277, mounted in recess 278 in the said clutch 275; clutch pin 277 has a wedgeshaped head 279 for engagement by a releasing lever 280 connected to a rock shaft 281 and manually operable by a handle 282. Bearing plate 263 also provides a bearing 283 for gear wheel 284, which is keyed to shaft 285; the shaft extends outwardly toward the side of the machine, and is provided with a hand wheel 286 for manual operation. Gear wheel 284 is provided with a pin 287, (shown in Fig. 7), adapted to engage lever 280 to remove it from contact with the head 279 of the clutch pin 277, during the rotation of the said gear 284 (see Fig. 50); by this means the pin 277 will be released and ready to drop into the recess 276 in gear wheel 276 at the completion of its second revolution during the threading-up process; this will automatically stop these various parts of the mechanism and position them for the normal operation of the entire machine.

The paper strip upon which the stamps are printed is fed from a roll held on a spindle 289 in a magazine 156 provided with a door 288. A signalling device 290 notifies the operator when the paper roll has been practically exhausted; at each operation of the machine thereafter a bell 291 is rung by a hammer 292, actuated by lever 293 upon contact with a pin 294 on gear wheel 270 (see Fig. 7).

The signalling device 290 further comprises a rocker arm 295 upon which the bell 291 and lever 293 are mounted; the arm 295 is pivoted, at 296, in a sleeve 297 in the magazine 156. Attached to the connecting shaft 298, on the inside of magazine 156, is a lever 299, having a roller 300 adapted to bear upon the upper surface of the paper roll contained in the magazine 156. When there is a full roll of paper in the magazine 156, the signalling mechanism is at the position shown in Fig. 7; as the paper roll diminishes, the signalling mechanism 290, being actuated by gravity, will gradually drop until the lever 293 comes within the path of the pin 294, whereupon the rotations of the gear wheel 270 will actuate the lever 293 to ring the bell 291.

A locking mechanism is also provided to prevent operation of the machine when the paper strips upon which the stamps are printed is not in its proper place, or when the supply of the paper tape is interrupted. This locking mechanism comprises a roller 301 designed to ride upon the face of the paper strip while it is passing between roller 304 and feed roller 274; feed roller 274 has a recessed portion 302 to receive the roller 301, which, being spring tensioned, drops into recess 302 upon discontinuance of the paper strip past that point (see Fig. 2). The roller 301 is mounted in a lever 303, pivoted at 304 in a portion of

the bearing plate 263 (see Fig. 6). Lever 303 is continued to form lever 305, which is connected to and operates pull rod 306. Pull rod 306 has a slotted end 307 for engagement with a pin 308 mounted in rock bar 309 which is supported by bearing 310 and is adapted to engage in toothed wheel 311 keyed to main drive shaft 158, thus forming a positive lock. Pull rod 306, being thus loosely connected to lock bar 309, allows other operations of lock bar 309 by means hereinafter to be described.

For effecting the printing operations of the numeral wheel unit 151, the dater unit 152, and the co-incident operations of inking unit 153, main drive shaft 158 has at one end a bevel gear 312 meshing with a similar bevel gear 313 keyed to secondary shaft 159, for driving the shafts in a one-to-one gear ratio, thus providing a simultaneous rotation of the secondary shaft 159 with the main drive shaft 158.

The rocking frame 190 containing dater unit 152 and numeral wheels 194, is provided with a cam lever 294 to receive the wiping action of cam 314 mounted on secondary shaft 159 for a printing operation.

For the inking of the numeral wheels 194 and the dater type 217, there is provided an inking pad 295, normally occupying a position directly beneath, but not in contact with, the type faces, allowing free rotation of the type wheels 194 (see Fig. 31). A cam 315 is shaped to give a short, snappy action to the cam lever 294 on frame 190, which operates with a slapping contact against the ink pad 295 to properly ink the type faces of the numeral wheels 194 and the dater type 217; on the further rotation of the cam 315, rocking frame 190 is allowed to return to its normal position, thus again spacing ink pad 295 and allowing the necessary room for it to travel out of the path of the numeral wheels 194 and dater unit 152 in their downward path in a printing operation; (see Figs. 30 and 31).

As hereinbefore described, the printed stamp is deposited on platform 168 severed from the paper strip by a knife 169. As best illustrated in Figs. 27, 28, and 29, knife 169 is removably attached to knife arm 317 mounted in bearing 318 in supporting frame 201; the other end of knife arm 317 has a cam lever 319 for contact with knife cam 320, keyed to secondary shaft 159. Knife 317 is normally tensioned upwardly by spring 321. The cutting edge of the knife 169 passes across the face of a shearing edge 322, integral with the rear section of discharge platform 168. Knife 169 is down, in cutting position, at the completion of a printing operation remains in that position until the next printing operation, serving, together with certain casing elements hereinafter to be described, to prevent unauthorized access to the machine at that point.

Registers

For registering the monetary value of the stamps printed, and for locking the machine after a predetermined amount of postage value has been printed on stamps by the machine, there is provided a register assembly comprising a permanent total register 323 and a downward counter 324 (see Fig. 40). The downward count register 324 is designed and constructed to be reset by a post-office official, or other authorized person, and, to distinguish it from the other meter 323, is accordingly designated herein as a reset meter.

The registers 323 and 324 are operated by means

associated with the selector unit 150. This means, best illustrated in Figs. 19, 20, and 21, comprises, in general, register engaging and actuating rack members and stepped elevators adjacent thereto so arranged and so connected to selector unit 150 as to be moved different distances and thus selectively positioned relative to the register engaging members, in accordance with the values set up in the numeral wheels by actuation of the particular keys depressed on the keyboard. To accomplish this result connections are provided from the selector unit 150 to the elevators 343 to reproduce in the latter the selective, differential movements of the former. The connections include a register set-up actuating selector 325, secured to slide 177 of the selector unit and having the same selective, differential movement as the numeral wheel selector finger 178, also mounted on slide 177. The register set-up actuating selector 325 contacts the faces 326 of rack bars 327. The rack bars 327 are provided with rails 328 operating in tracks 329 of frame 173; on their upper faces are vertical ratchet teeth 330 similar to the ratchet teeth 196. Proper retention of rack bars 327 in set position is effected by dogs 331 provided with springs 332; the locking dogs are released by a releasing device 333. The rack bars 327 are further provided with toothed racks 334 which engage pinions 335 on shafts 336, mounted in bearings 337 in frame 173; bevel gears 338 and 339 on shafts 336 and 340, respectively drive shafts 340, which are provided with pinions 341 engaging racks 342. The racks 342 ride in slide bearings 343 and are connected to face plates 344 slidably engaged in grooves 345 in elevators 346. The elevators, by this connection with racks 342, are slidably moved different distances and their stepped faces 353 are selectively positioned relative to the adjacent presser feet 354, in accordance with the movement of the key-controlled selector unit 150. The elevators are carried by elevator tables 349, their sliding movement on the tables being permitted by the slidable engagement of tracks 347 on the elevators in tracks 348 in the tables. The elevation of the elevators 346 to bring one of the stepped faces 353 of each elevator into operative engagement with one of the presser feet 354, is effected by toggles 350, actuated by cams 351 on shaft 352. (See Figs. 19, 21, 22, and 22A.) The elevators are lowered by the same cam-controlled means.

Each of the presser feet 354 is formed as an integral part of one of the toothed sectors 355. The rack segments 356 of which contact and actuate pinion gears 357, which may form an operative part of either of the registers 323 or 324. Sectors 355 are mounted upon bearings 358 in register supporting frame 359, which extends upwardly to form register bearings 359' for shaft 359''. (See Figs. 22 and 40.)

As shown in Figs. 19, 20, and 21, the selector unit 150 comprises a frame 173 which slidably supports a carriage 174, movable longitudinally of the machine, and a slide 177, movable transversely of the carriage. The slide 177 carries both the numeral wheel actuating selector 178 and the meter set-up actuating selector 325. Longitudinal movement of the carriage and its selector 178, by means of push rods 180, sets up the numeral wheels in numeral wheel unit 151. In order to actuate the several numeral wheels in succession, it is necessary that the selector 178 be successively positioned in alignment with each

of the rack bars 188. This is accomplished by a transverse step by step movement of slide 177, by which the selector 178, carried by the slide, is moved, after each longitudinal operation of the carriage, from its position in alignment with one rack bar 188 to a similar position relative to the next rack bar of the series.

This successive positioning of the slide 177 is produced by escapement mechanism comprising a series of ratchet teeth 360 on the lower surface of the slide, and a spring-tensioned pawl or dog 361, pivoted at 362 to frame 173 and adapted to engage the ratchet teeth. Normally, the dog 361, when contacted with one of the teeth, is tensioned by the spring 365 pulling the slide 177 against it, and under this tension rests against the stop 366. When the slide 177 is held in this position by its spring 365 and dog 361, the tooth engaged by the dog is directly in line with a guide plate 363. Upon the longitudinal movement of carriage 174, to actuate one of the numeral wheels 194 by means of selector 178, the slide 177, which is mounted on the carriage, moves with the carriage, and carries the ratchet teeth away from the dog. When this occurs, the particular tooth which was at the time in engagement with the dog will be moved to rest against the guide plate 363, and will slide along this plate for the length of its travel with the carriage. Since this plate 363 is in line with each of the ratchet teeth 360 as they are consecutively held in position by the dog, the sliding of the previously engaged tooth along the guide plate will take place, whichever tooth is engaged.

When the tooth is thus disengaged from the dog 361, the latter is moved by its spring 364 to a position out of the path of the teeth, and away from the tooth that it formerly engaged. Hence, when the tooth that was formerly engaged by the dog is brought back by the return of carriage 174, it returns along the guide plate to its original position where it formerly engaged the dog, but in its returned position does not engage the dog. Upon leaving the guide plate, therefore, the ratchet tooth is momentarily unrestrained. In this situation the slide 177, by the tension of its spring 365, is moved laterally, bringing the next adjacent tooth into engagement with the dog. The tooth and dog then move together until the dog comes into contact with stop 366, by which the tooth now engaged is brought into alignment with guide plate 363. This positions the selector 178 in front of the next succeeding numeral wheel rack 188, ready for the next operation.

Each manipulation of the keyboard, by depression of a key during the setting up operation, moves the carriage 174 in its longitudinal path a distance equivalent to the number of the key depressed. Upon the return of the carriage to its starting position the slide 177 automatically moves transversely a distance of one tooth, and therefore moves the selector 178 into position to contact the next succeeding rack bar 188. Repetition of this escapement movement in the setting-up operation finally brings the selector slide 177 to the limit of its transverse movement.

Register set-up actuating selector 325 is thus automatically moved by the escapement in a transverse path from its normal position (shown in Fig. 19) successively to the points at which the respective numeral wheels 194 will be operated by selector finger 178 to set up the zone and weight in pounds. At this point in the movement of the selector 325 the fourth tooth 367 is brought into contact with the dog 361, positioning the

selector 325 in front of the face 326 of the first rack bar 368 to be acted upon, namely, the one corresponding to the number of dollars to be printed on the stamp; the next successive operation by the selector unit 150 brings the next or fifth tooth 369 to engagement with the dog 361, thus bringing selector 325 to engagement with rack bar 370 for a similar operation; the final movement brings tooth 371 to engagement with dog 361, thus positioning selector 325 to operate the last rack bar 372, which is the cents unit.

Connecting shafts 340, (see Fig. 40), are provided on one end with bevel gears 373 driving similar gears 374 on shafts 375 journaled in bearings 376 in indicator frame 377; shafts 375 are provided with bevel gears 378 connecting with other bevel gears 379, each connected respectively by sleeve shafts 380 to the indicator wheels 381, mounted upon shaft 382 in indicator frame 377.

The permanent register 323 has its first three numeral wheels so constructed that they are irreversible. The first numeral wheel 383, (Fig. 43) the cents wheel in the series, is actuated in its registering movements by gear wheel 384 operated by one of the rack segments 356 (Fig. 22). To provide for the necessary return movement of the segments 356 while in contact with gear 384, numeral wheel 383 is provided with internal ratchet teeth engaged by ratchet dogs 386 pivoted on a portion of gear wheel 384, namely the ratchet support 387. These parts are assembled with the sleeve bearing 388. Numeral wheel 383 has the customary indented tooth 389 peculiar to register wheels of this type, for the purpose of carrying over the tens unit to the next numeral wheel by engagement with pinion 390.

The next numeral wheel 391, the tens of cents, is provided with a drive gear 392, internal ratchet teeth 393 and ratchet dogs 394, identical with the corresponding parts associated with gear wheel 384. For the purpose of carrying forward the cents carry-over from decimal wheel 383 and pinion 390, there is provided a gear wheel 395, and, connected by sleeve bearing 396, ratchet dogs 397, of practically the same construction as those of the gear wheel 384 and its connecting parts. Dogs 397 contact the internal ratchet teeth 393 and provide means to independently operate numeral wheel 391 by means of either drive gear wheel 392 or pinion engaging gear wheel 395. Numeral wheel 391 is provided with a carry-over indented tooth 398 similar to tooth 389, connecting with the next pinion 399.

The third numeral wheel 400, the dollars wheel in the series, has the same construction as numeral wheel 391 with its attendant parts, and is so designed that its drive gear 401 may be driven by one of the rack segments 356 (Fig. 22). A set of numeral characters 402 running from "0" to "9" inclusive, are provided on all of the register wheels, thereby providing means for visual reading of the amounts registered in the registers. Numeral wheel 400 is provided with an indented tooth 403, of the same character and for a similar purpose, as the tooth 389; by this means the succeeding numeral wheels of the series are driven through their respective pinions. All of the numeral wheels are provided with ratchet faces 404 and teeth 405, to engage a dog 406 providing a non-reversible positioning means whereby the numeral wheels will retain their proper position and not be reversed by any action of friction from any of the associated parts.

The re-set register 324, is constructed to operate with a downward count movement of its

numeral wheels; the register is constructed to be re-set by an authorized person, it is provided with a complete set of drive gears identical with those for the register 323, and in addition contains between each of the numeral wheels and its attendant gearing, a lock controlling disc 407 secured to or integral with each numeral wheel. Each of these discs 407, (see Fig. 41), is provided with a notch 408, into which tumbler bar 409 enters when the said re-set register 324 has exhausted a pre-set and predetermined amount of postage, when all of the notches 408 will be in line for the tumblers 409 to enter. The movement of the tumblers 409 into notches 408 which are non-rotatably secured to shaft 410 rotates the shaft 410 to which they are non-rotatably secured, to operate a locking mechanism connected to the shaft. For the purpose of providing authorized access to the re-set register 324, the front section of the case 400 (Figs. 1 and 41) is provided with a lock door 411 which, when opened, as shown in Fig. 41 operates through lever 412, pinion engaging lever 413, numeral wheel locking spring 414 and register lock release lever 415 to disengage the numeral wheels so that they may be rotated to a position registering any desired number to be placed thereon; lever 413 also acts as a bearing 416 for shaft 417 on which register pinions 418 rotate. The opening of the door 411 to rock lever 413 on its bearing 416 disengages pinions 418 from their connecting register gear wheels 419, the engaging lever 413 together with spring 414 positioning the pinions and retaining them in alignment to properly engage the teeth of the gear 35 wheels 419 when the door 411 is closed and the register and its various parts are again placed in operating position.

The elevators 346 are operated in their vertical movements by cams 351 on shaft 352, which is driven by bevel gears 420 and 421 connecting with secondary shaft 159 (see Figs. 2, 22 and 23). The cams 351 comprise three individual cams: 422, 423, and 424 the cams laterally spaced to engage adjacent elevator tables 349 (see Figs. 22 and 23) are so arranged that they will progressively operate the elevators 346 to actuate first, by cam 422 the unit wheel of the series of numeral wheels contained in either register; second, by cam 423, the next register wheel, the tens of cents wheel, and upon the completion of its movement, the third, or dollars wheel, actuated by cam 424. This arrangement of successive movements provides and allows the necessary interval of time carry-over from one numeral wheel to the next.

Locking mechanism

For the locking of the drive mechanism of the machine, namely, the crank 248, the main drive shaft 158, the secondary shaft 159 and their connecting parts, between operations of the machine, there is provided a progressive release locking mechanism 163 (see Figs. 2, 15, 15-A, and 32). The main drive shaft 158 has a non-reverse means comprising a ratchet wheel 425 keyed to the shaft and contacting a spring tensioned dog 426, pivoted in frame 427.

The ratchet wheel 425 is provided on one face with a lock pin 428, which is engaged by locking bar 429 when in locking position; locking bar 429 operates laterally in bearing posts 430 and 431, is normally tensioned toward one end by spring 432, and has one end shaped with a face 433 adapted to be engaged by either one of two pins 434 or 435. These pins are mounted on one side

of a toothed wheel 436, rotatable on shaft 437 which is mounted in bearing posts 438. The wheel 436 has external ratchet teeth 439 engaged by the pawl 440 pivoted in slide bar 441 operating in track 442, see Figs. 15 and 32, and tensioned by spring 443. Bar 441 is connected to a lever 444, which is keyed to a rock shaft 445, which in turn is connected to and operated by key operated butterfly 446, as best shown in Figs. 2 and 4. There is also provided a lever 447, see Fig. 15, which is actuated by contact with lock pin 428 at certain points of its revolution to actuate the rock shaft 445, to which it is keyed.

A lever 448, connected to error rock shaft 161, 15 operates a rack bar 449 supported in bearing post 450. A rack 451 on the rack-bar engages pinion 452, which carries ratchet dogs 453; the dogs engage internal ratchet teeth 454 integral with a ratchet wheel 455 directly connected to 20 the toothed wheel 436.

For the purpose of locking the key bars 140 and their keys 137 immediately upon the completion of the operation of stamp printing, the main drive shaft 158 has keyed to it a cam 456 (see Fig. 25), which contacts a roller 457 mounted in an arm 458, slidably supported in bearing post 459; arm 458 is connected with a crank lever 460 keyed to a rock shaft 461. This rock shaft is connected with butterfly 462, which it operates to engage 30 and lock the key bars 140. The cam 456 is so shaped as to release the key bars 140, by disengagement of butterfly 462, upon the completion of a cycle of operation of the machine.

To clear the machine upon completion of a 35 printing operation, the main drive shaft is provided with cam means for operating the error rock shaft. This means comprises a cam on the main drive shaft, engaging a roller 464 on a lever 465 connected to error rock shaft 161.

40 For locking the machine there is provided a key lock 469 with a barrel 468 to which is secured a lever 466, to operate butterfly 462 by pin 467. The pin raises the butterfly 462 to a position against the key bars 140, (best shown in Fig. 46), preventing any movement of the key bars or of the keys 137. When the keys are thus locked by key lock 469 and the main drive shaft 158 is locked by lock pin 428, any and all operation of the machine is positively prevented.

50 For locking the numeral wheel rocking frame 190 against operation when the entire machine is at rest, there is provided a lock bar 220, (shown in Figs. 2, 25, and 26) and means for operating it by the main drive shaft 158 at the completion 55 of its cycle. This means comprises a cam 470 keyed to main drive shaft 158; the cam operates a push rod 471 which contacts with the lock bar 220 as shown in Fig. 2, and causes it to engage lock pin 219, shown in Figs. 25 and 26. The cam 60 470 is so shaped that it will lock the numeral printing unit 151 only when the drive shaft is in the normal rest position, thus preventing the possibility of unauthorized printing of stamps from the numeral wheel unit 151 without registering 65 in the registers the monetary value of the stamps printed. This locking mechanism is fully protected from unauthorized access by casing members hereinafter to be described.

The register locking shaft 410 (Figs. 41 and 70 42) is connected with a crank lever 472, which has a sliding contact with lock bolt 309 in (Fig. 6), adapted to engage toothed wheel 311 on main drive shaft 158. Locking bolt 309 is connected through rock shaft 474 (Fig. 2) with butterfly 75 473, (Fig. 4) which is adapted to lock key bars

140. Butterfly 473 is operated to locking position by the feed roller trip 301. By its connection with the register lock 410 it is also set to locking position by the re-set register exhausting the predetermined amount of postage for which it was set.

Clearance of the machine

The machine is cleared, either upon the completion of an operation of stamp printing, or upon operation of the error key 139. The clearing mechanism comprises a rock shaft 161 to which are connected or affixed the various parts operable by both the said error key 139 and a cam 463 on the drive shaft 159. The error key 139, and its key bar 140, operate, by contact, a small butterfly 475 which is mounted on and rocks shaft 161.

Cam 463 engages the roller 464 mounted in lever 465, which is secured to rock shaft 161. Lever 465 is also connected with a push rod 478, which has a face 479 adapted to contact a similar face 480 on dog release bar 481, which is mounted on rocking frame 190 in bearing 482. The bar 481 is provided with fingers 483, which contact pins 484 in ratchet dogs 197 to move them to a position out of contact with vertical teeth 196 in rack bars 188; operation of this mechanism allows the numeral wheels 194 to return to their original position. See Figs. 2, 18, 30 and 30.

There is further provided a means connected to the rock shaft 161 to return the selector slide 177 to its original position. This means comprises a lever 485, making a connection between lever 477 and a shaft 486 connected with a bell crank lever 487. This lever is adapted to pick up the slide 177 by means of pin 488, at any point at which it may be when the machine is cleared by error key 139, or from its final position when the machine is cleared by operation of the main drive shaft 158.

As hereinbefore described under "Locking mechanism", the progressive release lock 163 shown in Fig. 2 is provided with restoring mechanism comprising rack bar 449, pinion 452, dogs 453 and ratchet teeth 454, as shown in Fig. 15, which operate to move the toothed wheel 436 upon which are mounted pins 434 and 435, designed to contact locking bar 429 to engage lock pin 428 connected to the main shaft 158 as shown in Figs. 15, 15-A, and 32.

For the purpose of returning the progressive release lock mechanism 163 to original position upon the clearance action of either the main shaft 158 or error key 139 actuating shaft 161, there is provided a lever 448 secured to rock shaft 161 and actuating rack bar 449, as shown in Fig. 15. Thus the action of clearing the machine moves rack bar 449, and consequently the dogs 453, which pick up ratchet teeth 454 on wheel 436 at any point at which they may be and rotate them to a predetermined point, which consequently rotates pins 434 and 435 to their original position as shown in Fig. 32.

To simultaneously clear or allow the return of the indicator wheels 166 to zero point, and to restore the elevators 346 together with the rack bars 327 in the selector 150, to their original positions there is provided a releasing device 333 having a push bar 489 similar to the push bar 481, which is actuated by lever 478, and which moves ratchet dogs 331 out of contact with vertical teeth 330 in rack bars 327, allowing the rack bars to return to their original position. By this

means the register set-up mechanism is cleared preparatory to another operation of the machine. See Figs. 2 and 21. This clearance operation of the register set-up is necessary in view of the 5 possibility of error on the part of an operator; hence the provision of the visual monetary indicator 166, and the error key 139.

Casing elements

10 As best shown in Fig. 1, there are provided casing elements comprising the base plate 70 upon which the mechanism of the machine is mounted and which acts as a casing for the under part of the machine, and an upright front 15 section of casing 490 which may be an integral and permanent part of the base 70 and to which is secured a plate 491, through which the key bars 140 extend (see Figs. 1 and 4). Casing 490 has a port 492 for reading the permanent register 20 323, a similar port 493 for reading the re-set register 324, a lock door 494, which provides authorized access to the re-set register, and a discharge port 495 through which the printed stamp 25 is discharged.

25 The main casing of the machine 496, which is preferably of one piece construction for the four sides thereof, including the curved key board section 497, is designed to be lifted as a whole clear of the machine and base 70 after 30 platform 79 has been removed and the removable casing has been unlocked, locking means comprises a hand wheel 498, (Figs. 2 and 4), having connected to it a lever action, (Fig. 47), comprising a disc 499, to which are connected 35 levers 500 and 501.

40 Lever 500 operates a connected lever 502 and a latch 503, which contacts a bolt 504 on casing 496; by means of a rock shaft 505, lever 500 also operates a similar catch 506 against a bolt 507 on casing 496; catch 506 is mounted on post 74, and the catch 503 on post 75. Lever 501 operates a catch 508 mounted on post 76, which catch engages bolt 509 on casing 496; by means of shaft 510 lever 501 also operates a similar 45 catch 511 against a bolt 512 secured to casing 496. Catch 511 is secured to post 73. Access to the hand wheel 498 is furnished by lock door 513 in casing 496, provided with lock 514 and bolt 515.

50 Casing 496 is further provided on the left hand side of the machine with a lock door 133 (Figs. 4 and 6), and on the right hand side with a door 134, having a lock 132, and providing authorized access to the scale mechanism on that side of the 55 machine.

The key board section 497 of the casing 496 is provided with a port 516 (Fig. 1) for reading the dial 96; this port has on one side a set of figures denoting the various zones, acting as an index 60 517 for the readings on the dial as they appear in the opening 518 of the port. Through another port 519 readings may be had of the indicator 166. On the right hand side of the casing 496 is an opening 520 through which crank 248 may be 65 inserted; on the front section of the casing is an opening 521 through which the handle 124 may be inserted.

The base plate 70 may be provided with legs 522, (Fig. 1), with an adjustable foot 523 operable by a knurled thumb-disk, worked through port 524, which rotates a screw separator and thus moves foot 523 relative to leg 522 to raise and lower or to level the machine.

On the left hand side of the machine is an 70 other lock door 525 (Fig. 47), secured by hinge

526 to the base plate 70, this door having a lock 527 to engage a catch 528 on both posts 74 and 75; through this door access may be had to certain parts of the mechanism, namely, the paper roll magazine 156, conveyor unit 155, ink well 231, dater 152, ink pad 205 and water tank 170, for the purpose of replenishing supplies therefore, or for making necessary adjustments.

Access to this portion of the machine is termed "authorized access", as it is necessary in the 10 ordinary use of the machine. "Unauthorized access", which is access to any other part of the machine, is positively prevented except by an authorized person provided with the keys therefor, by means of certain permanent casing elements, best shown in Figs. 45 and 47. The fixed casing element 71, for example, comprising sections of steel plate, encloses vulnerable parts of the printing mechanism, and prevents access to parts of the mechanism lying immediately adjacent to those described as requiring frequent attention. The registers are housed in a permanent casing 165; the only access thereto is had through door 494 to that section of the casing which surrounds the re-set register 324. 15 It is the intent of my invention to provide efficient means for operation, positively prevent unauthorized access to the vital parts, and, at the same time, provide a means whereby an authorized person, such as an inspector of the Post 20 Office Department, may have the necessary access to the machine for the purpose of re-setting the re-set register, and inspecting and adjusting the scale mechanism.

35

Miscellaneous

Fig. 48 shows a portion of the key board section 497 of the casing 496, the port 516 and index 517, a series of figures on the dial 96 show through the opening 518, as they appear in operation. 40 Port 516 has a hair line indicator 529, for use in reading the figures indicated on the dial.

Operation

Having described the various elements comprising my invention, together with the parts composing the same, I will now describe the operation of the machine when a package is weighed and a stamp is printed.

It will be assumed that the entire mechanism 50 of the machine is properly assembled on bed plate 70, with the removable casing element 72 in proper position, that the scale platform 79 is in place, and that a package is placed upon platform 79. By means of the scale mechanism, 55 dial 96 rotates to the proper point to indicate the weight of the package in pounds. This rotation of the dial 96 brings into position opposite the index 517 a figure denoting the weight; the row of figures on the dial 96, which simultaneously appear in port 518 to the right of the hair line 529, denote the monetary value of the stamp to be printed according to the weight of the package and the zone to which it is to be delivered.

The operator of the machine, upon placing a package on the platform 79 and reading the monetary values on dial 96, refers to the official parcel post guide of States and zones, to determine by point of destination relative to the point 70 of origin the zone number to which the particular package is to be delivered; having determined the zone number reference is made to the index 517; the figure on the dial 96 opposite the determined zone number indicates the monetary 75

value of the stamp to be printed. The operator then operates the key board 137 to set up the proper combination of numerals within the numeral wheel unit 151, preparatory to the printing 5 of a stamp. This setting up operation of the key board 137, in the particular embodiment of the invention disclosed, always involves six steps.

First, there must be punched in on the key board the zone number, which is printed under the word Zone, (see Fig. 33). For an example of the machine operation, take the combination of figures shown in Fig. 33, namely, Zone 8; Weight 22 pounds; Amount \$2.65. To print the zone number, the key 138—8 bearing the figure 10 "8" will be punched first, thereby operating, through key bar 140, the connecting levers 184 and 183 and push bar 180. The movement of push bar 180 moves carriage 174, carrying slide 177 and selector arm 178. The initial position of 15 these parts is illustrated in Figs. 12 and 19. The selector arm 178 and its associated parts being in the original position shown in Fig. 12, the punching of the key 138—8 moves the selector arm 178 laterally to an extent determined by 20 the differential lever arm 184 which connects keybar 140 with push bar 180. Each lever arm 184 having different dimensions these levers transform the uniform movement of the keybars into differential movement of the push bars. 25 Consequently, when the "8" key is punched in and its keybar 140 is operated, the particular push bar 180 connected therewith moves the selector arm 178 to such an extent that the first numeral wheel is rotated to a point where the figure "8" 30 type will be brought into printing position; the spring action of these various parts returns them to their original position upon the release of the key 138—8.

The escapement action automatically takes 35 place by means of the various parts illustrated in Figs. 19, 20, and 21; the teeth 369 and the dog 361 are the main operative parts of the escapement. The second position, as the result of the escapement action after the punching in of the 40 first key, is best illustrated in Fig. 20; slide 177 has moved laterally one notch and selector arm 178 is positioned in front of the second rack bar of the group 188 in readiness for the next operation on the key board 137.

Second, to punch in on the key board 137 the 45 number of pounds indicated on dial 96, two keys must be punched in, whether or not the number of pounds indicated by the dial 96 necessitates the use of one or two figures, such as 8 pounds or 12 pounds. In the illustration being 50 used where the stamp in Fig. 33 shows the weight of 22 pounds, the operator will first punch in a "2", using the key 138—2, which will operate the various connections just described for 55 the first operation, and which will thereby rotate the second numeral wheel in the series 151 to a point where the type face of the figure "2" will be rotated to printing position; but in the event that there is only one figure to be punched in for the weight of the package, the "0" key, 138—0, is punched by the operator.

Third, the next key to be punched, in the 60 series of six, denotes the other figure in the pound weight to be printed; in the illustration being used, key 138—2 bearing the figure "2" will be punched, and, by the same operation as described, will rotate the third numeral wheel in the series 65 151 to a point where the type face of the figure "2" will be rotated to printing position. Each 70 of these and the following operations of any of

the keys will automatically operate the escapement to allow the slide 177 to move laterally one tooth, as described in the first operation.

Fourth, to set up the monetary values of the stamp as indicated on dial 96, there are provided 5 three numeral wheels in the series 151 to set up the dollar sign and such numbers of dollars as may be necessary, including a "0" amount, should there be no dollars. Following the illustration used in Fig. 33, indicating the amount \$2.65, 10 the operator will punch the key 138—2, which will rotate the fourth numeral wheel in the series 151 to a point where the type face of the figure "2" will be rotated to the printing point. Should there be no dollars required in the amount to be 15 set up, it is necessary to punch the "0" key 138—0, which will rotate the same numeral wheel so that the dollar sign thereon will be rotated to the printing point in place of a figure, giving a final 20 reading \$65, namely, sixty-five cents.

Fifth, following the illustration used, the operator will next, to set up the fifth numeral wheel or tens of cents, punch key 138—6 bearing the figure "6", which, will rotate the fifth numeral wheel in the series 151 to a point where the type 25 face of the figure "6" will be brought to printing position. Should there be no tens of cents to be printed on the stamp, the operator will punch the "0" key 138—0, which will rotate this numeral wheel to bring the type face of the "0" 30 to the printing position, and a stamp with only a "cents" amount will be printed as \$.07, namely, seven cents. This same numeral wheel carries on its face the periods for punctuation or decimal marking of the monetary value.

Sixth, the operator now sets up the last figure to be printed in the series namely the cents; according to the amount illustrated, he will punch the key 138—5 bearing the figure "5" to rotate the sixth wheel in the series 151, to bring the 40 type face of the figure "5" to printing position. This brings slide 177 to the final position of its lateral operation.

As far as the external operation of the machine 45 is concerned, provided that the operator has correctly punched the keys as just enumerated, the only remaining operation for printing a stamp is to turn the crank 248 in a clockwise direction twice; by this operation the printed stamp is delivered upon the platform 168 in discharge port 50 495. The stamp may be moistened on its gummed under side by pulling it over and in contact with moistening roller 170.

Besides the manual operations just described, the operations of the machine include a series 55 of consecutive movements, which operate within one complete cycle of operation of the machine, i. e., upon one complete rotation of the main crank shaft 158. For clarity in enumerating these consecutive operations within a complete 60 cycle, Fig. 49 shows a diagram of the various operations.

Assuming the top of the circle to be the starting point, the first movement within the mechanism corresponds to the portion 531 of the cycle, 65 which indicates that upon the slightest movement of the crank 248 and the consequent movement of the main drive shaft 158, the key bar lock 462, by means of the cam 456, will lock the keys 137 against any operation until after the completion 70 of the printing cycle. Co-incidental with the first movement of the main drive shaft 158 and its connecting secondary shaft 159 there is an inking operation, (532 in the diagram of Fig. 49), which constitutes rotation of cam 315 against the 75

cam face 204 to move the rocking frame 190 a sufficient distance to bring the face of the type on numeral wheels 151 into contact with the ink pad 205 for inking purposes, and to return the 5 rocking frame 190 to its original position, thereby allowing the ink pad 205 to be moved laterally by cam 210 and its connecting parts, out of the path of the numeral wheels 151 and the dater 213, which have been inked, see Fig. 31.

10 This inking operation is necessarily rapid since the portion of the cycle of operation allotted to the inker (532 in Fig. 49) must not over-lap to any material degree that portion 533 of the cycle of operation allotted to the printing movements 15 of the numeral wheels of series 151. This portion 533 of the cycle of operation is designed to allow sufficient movement of the numeral printing unit 151 to complete a printing operation, but it may over-lap the next succeeding portion 534 of the 20 cycle of operation, namely, the movement of the conveyor and the operation of the rotary printer.

25 At the conclusion of this printing operation the ink pad 206 (Fig. 31) returns to the original position (operation 535) to receive the contact 25 of the type face upon the next operation of the machine.

The next portion (536) of the cycle of operation is provided for the meter operations.

30 The following portion (537) of the cycle of operation is provided for the clearance of the machine including the return of the register set-up, the clearance of the indicator 166, the re-setting of the lock mechanism 163 for the main drive shaft 158, the return of the numeral wheels 35 in unit 151 to original position, and the returning of the selector arm 178 and its slide 177 to their original position, so that the machine may be ready for the next printing operation.

40 Another portion of the cycle of operation (538), is provided for the knife 169 to sever the stamp from the balance of the paper tape; as indicated, the operation of the knife begins after the completion of the conveyor movement (534). The final movement (539) in the cycle of operations 45 is the release of the key lock 462.

45 The progressive release locking mechanism maintains the main drive shaft 158 in a locked position so that the crank 248 cannot be turned except when the machine is fully prepared to print a stamp. This mechanism locks the main drive shaft at all times except upon the completion of the operations of the key board, by punching in six keys. The lock mechanism 163 (Figs. 15 and 32) includes a pin 428 connected to the 50 main drive shaft 158, the pin being contacted by locking bar 429.

55 Two pins 434 and 435 (Fig. 32) mounted on one face of a notched wheel 436, are designed to contact and cause a lateral movement of the locking bar 429.

60 The butterfly 446 initiates the necessary movement of locking bar 429, when the operator has punched in the requisite number of keys on the key board 137. Butterfly 446 is contacted by all 65 of the key bars 140 except the error key 139; upon the movement of any one of the key bars 140, the pawl 440, (Fig. 32), contacting one of the teeth 439 in wheel 436, moves it a distance of one tooth, thus moving either one of the pins 434 and 435 which happens to be in the original 70 position of pin 434 illustrated in Fig. 34; upon one more movement of the pawl 440, pin 434 is moved to a position as shown by a dotted pin 540; thereafter, upon the operation of each of 75 six consecutive keys of key board 137, the pin is

moved a distance of one tooth of the wheel 436 until it has made four such movements and reached a point as denoted by the dotted pin 541 in Fig. 32.

At this point pin 434 contacts the face 433 of 5 the locking bar 429; thereafter, upon the operation of a fifth key of the key board 137, the pin is moved one more point to the position indicated by the dotted pin 542; upon the punching of the 10 sixth consecutive key of the key board 137, the pin is moved one additional point to the position indicated by dotted pin 543 in Fig. 32; at this point the pin, by contacting the face 433, has moved locking bar 429 to the position indicated by broken lines 544 and 545, where the locking 15 bar 429 has cleared the lock pin 428 (as shown by the broken lines at 546-547 in Fig. 15-A).

To return the locking mechanism 163 to locking position, which is done during the cycle of operation after the locking pin 428 has passed 20 the plane of the locking bar 429, the arm 447 contacts the pin 428, and is actuated by its movement to move pawl 440 one tooth in the wheel 436. The pawl thereby rotates the wheel 436 so that either one of the pins 434 or 435 which is in contact with the face 433 of locking bar 429 will be rotated to original position, and consequently out of contact with face 433; this allows the locking bar 429, by the action of spring 432, to return to its normal position (Figs. 15-A and 32). Bearing 30 in mind that the wheel 436 has fourteen teeth and that it is rotated six steps by six successive key actuations, at the end of these actuations pin 434 or pin 435 is one step distant from a new starting position. As just explained, this one step 35 movement of wheel 436 on which these pins are positioned is effected by pawl 440, operated by arm 447 under the influence of pin 428 on wheel 425 (see Figs. 15 and 15-A). By this means is provided not only a positive lock for main drive 40 shaft 158, but also a positive positioning means whereby the entire operation of the mechanism of the machine is definitely stopped at a predetermined point in each cycle of its operation, and the various parts comprising the mechanism are 45 correctly positioned.

The progressive release locking mechanism 163 is returned to original position by means of the error key 139, which through its key-bar 140 engages butterfly 475 to operate the rock shaft 161 50 (Figs. 2 and 18). Shaft 161 is connected to the rack bar 449, which actuates a pinion 452, to which are connected the dogs 453, for rotating wheel 425. The dogs 453 are so designed that when the error key 139 is operated—regardless of the position of 55 the mechanism of the machine—the dogs will rotate and engage teeth 454 at whatever point they may be. By this operation wheel 425 will be rotated and the consequent movement of pins 434 and 435 will return the lock bar 429 to original 60 locking position.

The machine is designed to use a roll of paper tape gummed on one side, and of a proper width. The roll is held by a magazine 156, which, for convenience in loading, is provided with a spring 65 door 548, which holds a roll of paper on the spindle 289. The paper feeds out through slot 549 in the magazine provided with a friction roller 550 (see Fig. 7). To thread up the machine for operation with the paper strip, a roll is placed in 70 the magazine, and the end of the paper is inserted between the small safety roller 304 and the drive roller 274, and carried underneath and between the roller 274 and the belt 251 of conveyor unit 155. To operate the conveyor to carry the 75

paper strip forward into printing position without operating the entire mechanism of the machine, there is provided a clutch release for that portion of the drive mechanism which comprises the gear train from the drive shaft 158 to the rotary printer 226 and the conveyor belt 257.

This clutch release (Figs. 2 and 50) operates the clutch 275 on main drive shaft 158. The release mechanism has a handle 282, which, when shifted, operates to withdraw the pin 277 from the gear wheel 287, which drives the gear train. This leaves the gear train free to rotate independently of the drive shaft 158.

Manual operation of the said gear train in threading the paper strip is effected by a hand wheel 286, which, when rotated one turn in a counter-clockwise direction, rotates the gear train to turn the rotary printer twice, and to cause the conveyor belt 257 to move forward twice; thus the paper strip is carried a sufficient distance to receive two impressions of the rotary printer, and is placed beneath the dater and numeral wheels 151 a partly printed stamp ready to receive the figures set up in the numeral wheels by operation of the key board 137. The gear wheel 284, driven by hand wheel 286, has on it a pin 287, which, at a certain point of its cycle of operation, engages clutch lever 289, and moves it to disengage the head of the clutch pin 277; thus released pin 277 will engage the recess 276 in gear wheel 267 upon the completion of its second rotation, thus positively positioning the mechanism in relation to the main drive shaft for subsequent operation thereby (Figs. 2 and 50).

The intermittent movement of the conveyor belt 257 is effected by intermittent gears comprising the gear wheel 269 rotatably mounted on shaft 158 and mutilated for a portion of its surface, a second drive gear 270 with a stub bearing in frame 263 and having a portion of its surface on one side mutilated to fit the pitch line of the gear 269. The gear 270 connects by means of gear 271 and gear 272 to gear 273 all mounted in frame 263. Gear 273 is integral with the conveyor belt drive drum 259 (see Figs. 2 and 6).

Gear 272 drives drum 274, underneath which the paper strip passes; this drum is a split drum, having an open section 302, adapted to receive a wheel 301 (Fig. 2), which normally rides against the paper strip when it is threaded into the machine. Should the paper strip break or for any reason discontinue to pass that point, the wheel 301 drops into recess 302; this movement moves lever 305 and link 306 operates lock bolt 309 to set against one of the teeth in toothed wheel 311 on main drive shaft 158. Rotation of the drive shaft is thus prevented upon a failure of the paper feed.

The rotary printing drum 226 rotates continuously during the rotation of the drive shaft 158; its indicia plate 227 is so disposed upon its surface that it comes to the printing point only at the time that the conveyor belt 257 is in motion.

The shelf or anvil 265, over which the conveyor belt 257 passes, acts as a platen for the different printers. The paper strip, as it passes along the conveyor 257, is guided by rolls 551 (Figs. 7 and 24) and by guide plates 552 (Fig. 30), the latter retaining the paper strip in alignment upon the conveyor.

The signal bell apparatus 290 warns the operator when the paper roll is nearing exhaustion (Figs. 6 and 7).

Reversing of the main drive shaft 158 is prevented by a ratchet non-reverse 162 (Fig. 2). For

the purpose of setting the type in the dater for the current date the dater 152 has a removable section 214, (Fig. 26), which carries removable type 217. Operation of the machine when the dater is not in the correct position in its recess is prevented by the spring pin actuated by the dater to move locking bar 220. This bar engages beneath the dater frame at 222, and is disengaged only when the dater 214 is properly seated within its recess. 5

For changing its type the dater may be removed by a key, or like instrument (not shown) inserted and secured in a threaded hole 553 (Fig. 25).

Unauthorized operation of the numeral wheel unit 151 is prevented by a lock 471 actuated by 15 cam 470 on shaft 158, which locks the rocking frame 190 except when the machine is being operated to print a stamp.

For convenience of operation, and to comply with postal laws and regulations, I provide two 20 registers, of which one is a permanent register, and the other a resettable downward count register, both operated simultaneously from the numeral wheel selector mechanism 150. To allow for the possibility of errors in the set-up of the 25 numeral wheels by the operator, the register operating mechanism is divided into two separate units, of which one is a reversible set-up unit to be operated to put the amount into the registers and the other is the actuating unit to operate the 30 set-up to rotate the register numeral wheels in accordance with the amount that has been set up.

In case of error the set-up unit mechanism, best illustrated in Fig. 22 and comprising parts 341, 342, 343, 344, 345, 346, and 353, through the action 35 of the error key 139 and its connected parts is allowed to return to original position through spring action, thus clearing the register set-up mechanism for a new operation. The same action of these parts is repeated at the conclusion 40 of each printing operation of the machine, the main drive shaft 158 actuating the error rock shaft 161 by means of the cam 463, thus preparing the registering mechanism for the next printing operation. 45

The set-up unit of the register operating mechanism is actuated by a selector arm 325, (Figs. 19, 20, and 21), which is secured to and operated simultaneously with slide 177, thus making its movements coincidental with, and to the same 50 limits as, the numeral wheel actuating mechanism, and providing accurate duplication of the movement of the printer set-up within the register set-up mechanism. The selector arm 325 moves laterally to engage the racks 327, and 55 slides them to a point corresponding to the amount of the figure being punched in on a key of key board 137. The lateral movement of the slide 177 by means of its escapement positions the selector arm 325 to contact each of racks 327 successively. 60

The racks 327 are positioned and restrained against return movement by ratchet dogs 331, which are later moved by the error mechanism to release the racks 327 and allow them to be returned to original position by their spring tension. 65

The elevators 346 are actuated to put the set-up into the registers by cams 422, 423, 424 (Figs. 22 and 23). These cams are driven by connections from the main drive shaft 158, and are rotated in a successive manner, thereby providing an interval between the rotation of the first numeral wheel of a register and the next succeeding one for the carry-over, should there be one, to become registered upon the next succeeding numeral wheel; interference of the several numeral wheels 70 75

with each other or with the drive elements, is prevented by sets of ratchets within the several wheels. As the cams make a complete rotation, the elevators return to their original vertical position assisted by spring tension, thus allowing the segments 356 to return to original position (as shown in Fig. 22) under spring tension.

The re-set register is provided with a lock actuating device Fig. 41, comprising discs 407 with 5 notches 408, which, when the register has been exhausted of the amount of postage for which it has been set, rotate to a point where the tumblers 409 drop under spring tension into notches 408, and thus rock shaft 410. The rocking of this 10 shaft, through its connections, moves lock bar 309 into its locking position (Fig. 6), thus locking the main drive shaft 158 against rotation, and also rocks butterfly 473 (Fig. 2), to contact the key bars 140 and lock them against operation.

20 This effectively locks all movable parts of the machine against any operation upon the exhaustion of the amount of postage for which the machine has been set, and the machine can only be operated upon the re-setting of the re-set 25 register for an additional amount by an authorized person.

For the se-setting of the re-set register, access 30 to it is obtained by means of a lock door 411, (Figs. 1 and 41.) The opening of this door releases the register pinions, but restrains the numeral wheels of the register against unnecessary movements, and at the same time releases the locks set by the register; it also provides 35 ease and convenience in re-setting the register by exposing to the operator all the numeral wheels, which may be moved manually and individually to read the amount of postage for which the register is to be set the closing of the door automatically meshes the pinion gears 418 with their respective numeral wheel gear teeth 40 419, and the register is ready for use. The permanent register is a perpetual register, and is sealed within a separate case at the time the machine is built.

45 The visual indicator shows to the operator the monetary value of the stamp for which the amount has been punched in on the keyboard and has been set up both on the numeral wheels of the printer on the set-up for the 50 registers. This provides the operator with a check-up on his work, in order that he may correct any inaccuracies before the amount has been registered in the registers or the stamp printed. By means of the error key the machine 55 may be cleared for another operation. The indicator, being directly connected with the register set-up mechanism, is automatically returned to the zero position at each clearance of the machine.

60 For transferring movements at right angles to their source, from the key board 137 to the selector bank 150, a series of bell crank levers are provided. Three of these key connections, of different proportions namely, the longest, the 65 middle and the shortest action of the set are illustrated. Fig. 8 illustrates the longest, for the key 138-9 bearing the figure "9", and has the longest travel. Fig. 10 shows the one with the shortest travel, namely the key 138-0, being marked "0" 70 and operating to set up a "0" for printing.

75 The drawings depict one form of mechanism for registering only monetary values, but the same mechanism may be expanded to include any other registering operations that may be desired, without changing the structure or function of

the parts described, by merely adding duplicate parts or unit assemblages of the same mechanism. It is the intent of my invention to provide a machine with mechanism of a very flexible nature, in that it may readily be adapted to use 5 in any form of stamp printing, registering, or weighing operations. Stamps of any size, shape, thickness of paper may be used; gummed or un-gummed paper, ink of one or several colors may be used; the indicia plate may be of one color 10 and the date and figures in a contrasting color. The machine may be constructed of any size, of any number of pounds capacity, and of any desired shape, and may provide a weighing platform of sufficient capacity that parcels of any 15 size or shape may be weighed thereon without in any way obstructing the reading of the scale dial, the keyboard operation, or the delivery of stamps from the machine.

While my machine is intended primarily for a 20 stamp printing machine wherein the weighing mechanism may be used for the indication of the weight, and/or the amount of postage to be printed upon a stamp therein is governed by the distance to which the parcel or mail matter is 25 to be sent, the machine is of so flexible a character that it may be readily adapted to the printing of any desired matter of similar character or disposition; the scale may be used independently 30 of the printing mechanism for the purpose of weighing; or the scale and the printing mechanism may be in interlocking relation; or the scale mechanism may be used to operate the printing mechanism.

I have invented a machine for convenience, to 35 facilitate the mailing of parcel post packages, and to insure the greatest degree of accuracy, economy and speed in the operation thereof. My machine provides a means of eliminating 40 much of the excessive handling of postal matter and consequent loss of time; it eliminates the use of postage stamps now provided by the U. S. Government and the Post Office Department, and the consequent inconvenience and loss. Thus, 45 with one operation, a parcel is weighed, a stamp bearing the weight, zone and amount of postage is printed, and the stamp is affixed, dated and cancelled.

The structure of the several mechanisms illustrated and described herein may be varied in 50 form without departure from my invention as hereinafter claimed. The showing of this description and of the drawings is merely in illustration of one embodiment of my invention in 55 response to the statutory requirements.

I claim:

1. In a device of the character described, a series of keys, a movable carriage, a stepped member 60 slidable on said carriage, means for sliding said stepped member on said carriage a different distance by actuation of each key to selectively position said stepped member, registering mechanism separate from said stepped member and carriage, racks engaging said registering mechanism, one end of each rack being positioned adjacent the stepped portion of said stepped member, and means for moving said carriage to engage said racks with the stepped portion of said stepped member and impart to said racks and 65 said registering mechanism different degrees of movement dependent upon the selective position of said stepped member.

2. In a device of the character described, a keyboard mechanism including a series of keys 70 and keybars, registering mechanism including 75

register wheels, movable actuators for said register wheels, differential setting members actuated by the respective keybars, transfer members for selectively positioning said actuators, a selector device movable by said setting members toward said transfer members, means for moving said selector device transversely of said setting members to position said selector device for successive operation of said transfer members corresponding to the successive actuation of said keys.

3. In a device of the character described, a keyboard mechanism including a series of keys and keybars, registering mechanism including register wheels, movable actuators for said register wheels, differential setting members respectively actuated by said keybars, transfer members, a selector device differentially movable by said setting members toward said transfer members, said selector device being movable transversely of said transfer members to a plurality of positions successively, said selector device having a selector member positioned by said transverse movement to actuate said transfer members successively to move said actuators to positions corresponding to the successive actuation of said keys.

4. In a device of the character described, a single bank of keys representing numerals from "0" to "9", a series of register wheels, actuators for said wheels, transfer members for operating said actuators, a selector device differentially movable by said keys toward said transfer members, said selector device being movable transversely of said transfer members to a plurality of positions successively, said selector device having a selector member positioned by said suc-

cessive positioning of said selector device to move said transfer members in succession to positions corresponding to the successive actuation of said keys.

5. In a device of the character described, a series of keys and keybars, a series of register wheels, operating members therefor, stepped members, differential setting members actuated by the respective keybars, transfer members for selectively positioning said stepped members, a selector device movable by said setting members toward said transfer members, means for moving said selector device transversely of said setting members to position said selector device for successive operation of said transfer members to move said stepped members successively to positions corresponding to the successive actuation of said keys.

6. In a device of the character described, a series of keys and keybars, a movable carriage, a stepped member slidable on said carriage, means for sliding said stepped member on said carriage a different distance by actuation of each key to selectively position said stepped member, register mechanism including register wheels, movable actuator racks engaging said register mechanism, said racks being separate from and positioned with an end of each rack adjacent to the stepped portion of said stepped member, means for moving said carriage vertically to engage said actuator racks with the stepped portion of said stepped member and move said racks different distances dependent upon the selective position of said stepped member.

WILLIAM J. PEARSON.
